CONTROLLING FOAM IN SUBMERGED AND
AERATED PROPAGATION OF MICROORGANISMS

Willis O. Gordon, New Orleans, La., and Matthew K. Veldhuis, Winter Haven, Fla., assignors to the United States of America as represented by the Secretary of Agriculture

Application June 3, 1949, Serial No. 97,065

4 Claims. (Cl. 195—94)

(Granted under Title 35, U. S. Code (1952),
sec. 266)

1

This application is made under the act of March 3, 1883, as amended by the act of April 30, 1928, and the invention herein described, if patented in any country, may be manufactured and used by or for the Government of the United States of America for governmental purposes throughout the world without the payment to us of any royalty thereon.

This invention relates to the propagation of micro-organisms, such as yeast, in which the organism is propagated by culturing it submerged in a liquid nutrient medium, and air is continuously mixed with the medium to furnish the required oxygen. At certain stages during the growth of the organism, the medium tends to form a foam which is quite stable, resulting in considerable trouble and loss of the organism and medium by ejection of foam from the usual type propagator through the air vent. In prior art processes, antifoaming agents have been added to the nutrient medium to inhibit the foaming, but this is expensive and bothersome. This invention has among its objects a simple and efficient apparatus for controlling such foaming.

For a detail description of the invention, reference is made to the accompanying drawing, which schematically shows in a single figure the essential features of an apparatus according to the invention.

In the drawing, a plurality of corresponding propagator tanks 11, 12 and 13 for containing liquid medium are arranged in series. Any number, from one single propagator tank up to three, will generally suffice. The liquid nutrient medium continuously feeds into propagator tank 11 through inlet pipe 17, feeds continuously through such propagator tank, and feeds to propagator tank 12 through medium pipe 18, then to propagator tank 13 through medium pipe 19, and finally through medium pipe 20 to receiver tank 21, the time of passage and degree of organism propagation depending on the rate of feeding the nutrient medium and size of the propagators. Pipe 18 is connected to tank 11 at a point below its connection to second tank 12, and pipes 19 and 20 are similarly connected to tanks 12 and 13, and to tanks 13 and 21, respectively. Pipes 18, 19 and 20 are so arranged that the medium feeds through them by over-flow.

Air is continuously forced through air pipe 22, through branches 23, 24 and 25, and is introduced into the medium in the several propagator tanks through porous tubes 26, 27 and 28 at a rate sufficient to keep the medium well stirred and well

2

aerated, excess air and formed gases being vented from the propagators through vents 30, 31 and 32, if these vents are open.

As foam is formed in the propagator tanks, it rises on the surface of the medium and passes with an air stream at substantial velocity from propagator tank 11 to propagator tank 12 through a relatively large foam pipe 35, then to propagator tank 13 through foam pipe 36 and, if any is yet present, finally to receiver tank 21 through foam pipe 37, these foam pipes establishing communication between their respective tanks near their upper portions, each being connected to its propagator tank at a point above the liquid contained therein. It is this passage of the foam which causes it to disintegrate, and to this end targets 38 and 39, preferably perforated plates, are so mounted relative to pipes 35 and 36 that the foam strikes the targets and is disintegrated, and the resulting small amount of liquid drains into the liquid medium.

Medium pipes 18, 19 and 20 are provided with cut-off valves 40, 41 and 42, respectively, and it is possible to close these valves in operation of the apparatus so that the liquid medium also flows from the several propagators through foam pipes 35, 36 and 37. This increases the capacity of the apparatus due to the liquid level standing higher in each propagator than if pipes 18, 19 and 20 are used, and gives satisfactory operation if the amount of foaming is not too large.

Cut-off valves 45, 46 and 47 are also provided in pipes 35, 36 and 37, so that with closing of the proper valves any propagator may be isolated for cleaning purposes, etc.

In operation vents 30, 31 and 32 may be closed and the excess air and gases vented through pipes 35, 36 and 37. This is desirable if contamination through the vents is probable.

The successful operation of the apparatus in the propagation and production of micro-organisms such as yeast depends in part upon the impingement of the stream emerging from the foam pipe against the target at a velocity which will disintegrate the foam. This is accomplished by employing a foam pipe of cross sectional area such that the velocity of gas and foam passing therethrough is substantially greater than the velocity rising through the propagator. To this end the foam pipe should have a cross sectional area of from $\frac{1}{6}$ to $\frac{1}{3}$ that of the propagator tank. When employing propagator tanks of about three feet in diameter, foam pipes of from six inches to one foot in diameter may be employed to achieve highly satisfactory results. Employing an aeration rate of about 150 cubic

feet per minute, results in approximately 500 feet per minute velocity through the foam pipe. The relative dimensions of the propagator tanks, foam pipes and rate of aeration, may however be varied within wide limits, so long as the stream of air and foam impinges against the target.

The target may be preferably a perforated plate set at an angle within the receiver tank, or adjacent propagator tank as the case may be, and so positioned that the stream of air and foam strikes it upon leaving the propagator tank. The specific form of the target may be varied considerably. For example, it may be a screen, a series of perforated baffles or screens and the like of flat or curved contour. It is important that the impingement surfaces of the target be perforated or otherwise foraminous in order to achieve the most efficient foam disintegration.

Having thus described the invention, what is claimed is:

1. A continuous process of propagating micro-organisms comprising culturing them in a liquid nutrient medium contained in a propagator tank, continuously feeding liquid medium therein, continuously introducing air into the medium for aeration thereof, continuously passing produced foam and introduced air from the upper portion of the propagator tank to the upper portion of a second tank through a foam pipe communicating with the tanks to disintegrate the foam, and continuously feeding the liquid medium from the propagator tank to the second tank through a medium pipe, the liquid level in the tanks being maintained lower than the points of communication of the foam pipe therewith.

2. The process of claim 1 characterized in that the foam strikes against a perforated plate placed adjacent the outlet of the foam pipe to aid in disintegrating the foam.

3. An apparatus for the continuous propaga-

tion of micro-organisms by culturing them in an aerated, liquid nutrient medium, comprising a propagator tank for containing the medium, said tank having means for continuously feeding liquid medium therein and means for continuously introducing air into the medium for aeration thereof, and a second tank arranged in series with the propagator tank, the tanks communicating through a foam pipe connected to their upper portions, so that introduced air and foam formed in the propagator tank pass therefrom through the foam pipe into the second tank and the foam is thereby disintegrated, the propagator tank communicating with the second tank through a medium pipe connected to the tanks at points below the points of connection of the foam pipe to the tanks so that the liquid medium continuously feeds by overflow from the propagator tank through the medium pipe to the second tank, and the liquid level in the tanks is maintained lower than the connections of the foam pipe thereto.

4. The apparatus of claim 3 characterized in that a perforated plate is placed adjacent the outlet of the foam pipe against which the foam strikes thus to aid in its disintegration.
